DESIGN FOR BARBERS' CHAIRS.

Design No. **11,193**, dated May 13, 1879.

UNITED STATES PATENT OFFICE.

AUGUST WEKERLE, OF NEW YORK, N. Y., ASSIGNOR TO HIMSELF AND
SIMON KLINGLER, OF SAME PLACE.

DESIGN FOR BARBERS' CHAIRS.

Specification forming part of Design No. **11,193**, dated May 13, 1879; application filed December 9, 1878.
[Term of patent 7 years.]

To all whom it may concern:

Be it known that I, AUGUST WEKERLE, of the city and State of New York, have invented or produced an Ornamental Design for a Barber's Chair, of which the following is a specification.

In the accompanying photograph the design of the chair is represented in perspective.

The said ornamental design is a casting forming the frame of the chair. The front legs, *a*, and back legs, *b*, are curved outwardly, and terminate with ornamental feet *c*. The legs are connected by open-work at the sides and front. The sides are made with a shield-shaped open-work, *d*, with scrolls *e* at the upper part of the shield, and with scrolls *f* con-

necting the lower parts of the shield with the legs, and these scrolls terminate upwardly with arrows *h*, that cross behind the shield. The arching brace *i* unites the front legs, and there is open-work at *l* around the seat-frame, and lion-head ornaments *m* at the arms.

I claim as my invention or production—

The design of the open-work chair-frame, consisting of the shield *d*, scrolls *e* and *f*, arrows *h*, and curved legs *a* *b*, substantially as described and shown.

Signed by me this 3d day of December, 1878.
AUGUST WEKERLE.
